The ornamental design for a neck light, as shown and described.

DESCRIPTION

FIG. 1 is a front view of a neck light showing my new design;

FIG. 2 is a rear view thereof;

FIG. 3 is a left view thereof;

FIG. 4 is a right side view thereof;

FIG. 5 is a top view thereof;

FIG. 6 is a bottom view thereof;

FIG. 7 is a front, right and bottom perspective view thereof;

FIG. 8 is a front, left and top perspective view thereof;

FIG. 9 is a front, right and bottom perspective view thereof in use; and,

FIG. 10 is a rear, left and top perspective view thereof in use. The broken lines in the drawings depict portions of the neck light that form no part of the claimed design.
